UNITED STATES PATENT OFFICE.

HENRY M. FRASER, OF CINCINNATI, OHIO, ASSIGNOR TO THE ROYER WHEEL COMPANY, OF SAME PLACE.

DESIGN FOR A HUB-BAND.

SPECIFICATION forming part of Design No. 16,602, dated April 6, 1886.

Application filed November 30, 1885. Serial No. 184,371. Term of patent 14 years.

To all whom it may concern:

Be it known that I, HENRY M. FRASER, a citizen of the United States, and a resident of the city of Cincinnati, in the county of Hamilton and State of Ohio, have invented a certain new Design for a Vehicle-Hub, of which the following is a specification.

In the accompanying drawings, Figure 1, Sheet 1, is a side elevation of a hub illustrating my design. Fig. 2, Sheet 2, is a front elevation of the same hub, and Fig. 3, Sheet 2, is a vertical central longitudinal section of this hub.

D indicates the front end of the hub. A represents the point band of the hub. C represents the annular flange surrounding the hub in front, and C' represents the annular flange surrounding the hub at the rear.

The side of the surrounding flange C is pro-

vided with a bead, b, and this bead is located 20 at the outer edge of the flange. Below this bead b the outer contour in cross-section of the flange consists of the three curves e' e² e'. Between the bead b and the curve e' is the groove f.

What I claim as new, and desire to secure by Letters Patent, is—

In a design for a wheel-hub, a surrounding flange provided with an annular bead, b, between which and the inner edge of the flange 30 are the curves e' e² e', and between the bead b and the curve e' the annular groove f, substantially as described and shown.

HENRY M. FRASER.
